US0D1070821S

(12) **United States Design Patent** (10) **Patent No.:** **US D1,070,821 S**
(45) **Date of Patent:** **** Apr. 15, 2025**

(54) **EARPHONE**

(71) Applicant: **Apple Inc.**, Cupertino, CA (US)

(72) Inventors: **Wenjie Zhuang**, Pasadena, CA (US); **Robert Boyd**, Los Angeles, CA (US); **Duy P. Le**, Venice, CA (US); **Jeffrey Scott Croyle**, San Francisco, CA (US); **Joseph F. Dembs**, Los Angeles, CA (US); **Guillaume Raoult**, San Francisco, CA (US); **James Swasey**, Oakland, CA (US); **Christopher Kuh**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/958,964**

(22) Filed: **Aug. 22, 2024**

Related U.S. Application Data

(63) Continuation of application No. 29/883,297, filed on Jan. 26, 2023, now Pat. No. Des. 1,040,139.

CLAIM

The ornamental design for an earphone as shown and described.

DESCRIPTION

FIG. 1 is a top isometric view of an earphone showing the claimed design;

FIG. 2 is a bottom isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a bottom plan view thereof; and,

FIG. 8 is a top plan view thereof.

The broken lines in the figures show portions of the earphone that form no part of the claimed design.

1 Claim, 4 Drawing Sheets
